(57) **CLAIM**

The ornamental design for a washing agent container as shown and described.

DESCRIPTION

FIG. 1 is a top, front perspective view of a washing agent container showing the claimed design;

FIG. 2 is a bottom, rear perspective view thereof;

FIG. 3 is a right side view thereof;

FIG. 4 is a left side view thereof;

FIG. 5 is a top plan view thereof; and,

FIG. 6 is a bottom plan view thereof.

The broken lines in the figures show portions of the washing agent container that form no part of the claimed design.

1 Claim, 6 Drawing Sheets
